UNITED STATES PATENT OFFICE

2,251,990

MATERIAL UNLOADING SYSTEM

Frank De Young, Chicago, Ill.

Application October 26, 1939, Serial No. 301,465

1 Claim. (Cl. 214—44)

This invention relates to a new and improved material unloading system.

An object of the invention is to provide a new and improved material unloading system which is particularly adapted for the handling of coal though not necessarily so limited.

A further object of the invention is to provide an improved combination of parts which makes for the efficient unloading of coal and loading it into a truck or conveying it to any desired location which requires a minimum of effort, apparatus and power.

Still another object of the invention is to provide an improved pit and control mechanism for controlling the feeding of coal dumped from a car into a conveyor or other receptacle.

Still another object of the invention is to provide a new and improved conveyor or receptacle.

Other objects of the invention will appear hereinafter, the novel features and combinations being set forth in the appended claim.

In the accompanying drawings,

Fig. 1 is a schematic view showing the system of my invention and apparatus capable of carrying out my invention;

Fig. 2 is an enlarged plan view of the pit and associated apparatus forming a feature of my invention;

Fig. 3 is a transverse sectional view taken on the line 3—3 of Fig. 2 looking in the direction of the arrows; and

Fig. 4 is a longitudinal sectional view taken on the line 4—4 of Fig. 2 looking in the direction of the arrows.

Referring to the accompanying drawings, there is seen a pair of rails 10 on which a car, such as a coal car 11 preferably of the open or gondola type, is adapted to rest and to discharge coal therefrom by means of bottom discharging gates which are well-known in this type of coal car; that is, the coal car 11 is preferably of the hopper type having a bottom gate or gates which may be controlled to discharge the coal on the car tracks and the area adjacent thereto particularly the area between the car tracks.

Positioned directly below the car tracks or rails 10 is a pit 12 preferably formed of a monolith of poured concrete and having a pair of parallel side walls 13, 13. As clearly seen by reference to Fig. 1 of the drawings, I provide an elevating type of conveyor 14 which has a substantially horizontal material receiving portion 15 adapted to extend between the side walls 13, 13 of the pit 12 and having material guide plates 16 adjacent each

lateral edge adapted to fit fairly close to the walls 13, 13 to prevent spillage of material.

It is evident that any material received in the receiving portion 15 of the conveyor will be conveyed by the conveying mechanism thereof which is preferably in the form of scraper type flights which scrape the material over a trough bottom and deliver it at an elevated position to a truck or other receptacle 17, the material such as coal being seen at 18 in Fig. 1 of the drawings. It is of course evident that the conveyor 14 may discharge to any other receptacle or to a storage pile, but it is particularly adapted to elevate the coal and discharge into a relatively high bodied truck, and in order to do this the flights on the endless conveyor mechanism are relatively high, for example, they may have a height of 3½", since the slope of the conveyor boom is relatively steep.

With a flight of this type it is necessary to prevent the weight of the coal as dumped from the car 11 being received directly onto the receiving portion 15 for this weight is so great that the flights of the conveyor 14 would be torn loose or destroyed in a very short time. It is therefore necessary to control the feeding of the coal into the receiving portion 15 at a controllable rate so as to preclude any damage to the conveyor 14 under conditions as above described.

In order to effect this controlled feeding of the material receiving portion 15, the pit 12 is provided with a horizontally positioned variable size slide valve 19. The slide valve 19 comprises a pair of angle members 20, 20 (see Fig. 3) positioned adjacent the bottom flanges of the rails 10, 10 between which extend a pair of stationary plates 21 and 22 (see Fig. 4) which are rigidly attached as by welding to longitudinally extending bars 23, 23 welded to the upright flanges of angle members 20, 20.

Slidable beneath the bottoms of the bars 23, 23 and on the horizontal flanges of the angle members 20, 20 is a movable plate 24 to which is attached an operating rack 25 operable by a pinion 26 carried by a shaft 27 which is journaled in bearings 28, 28 rigidly attached to the stationary plate 22. The shaft 27 is connected by a universal joint 29 to an operating shaft 30 which carries an operating lever or hand wheel 31 which is located at a remote position with respect to the valve 19 thus permitting its operation even though the valve 19 is substantially covered with coal.

The left-hand portion of the pit 12 is covered by a removable cover plate 32 which permits access for lubrication of the tail bearings of con-

veyor 14 in case the conveyor is left in position and not removed as it may well be for a long period of time in actual practice. The rails 10 will be supported by the usual railroad ties directly on the ground and the area in between the normal ties will be filled in with dirt or stone or other material so that as the coal is discharged from the car 11 a support for it will be formed by the road bed and the plate 32 as well as the valve 19; that is, when the valve 19 has its adjustable plate 24 in valve closing position in which case the left end thereof as seen in Fig. 4 abuts the stop 33, the coal discharged from the car 11 is supported on a support formed by the ground, the plate 32, the plates 21 and 22 and the plate 24. By adjusting the plate 24 under the control of hand wheel 31, it is evident that the coal thus supported and particularly the coal between the tracks 10 may be discharged to the receiving portion 15 of the elevating conveyor 14 at a controlled rate.

It may be stated that in general the coal will be discharged from car 11 between rails 10 though of course there will be some spillage outside said rails. It is to be particularly noted that by virtue of my system and method, no feeding conveyor is necessary, but the material flows by gravity until it is received by conveyor 14 and thus a single conveyor is required to transfer the coal from the car 11 to the truck 17.

In the operation of the material unloading system of my invention, the coal is discharged from the hopper type open or gondola cars 11 onto a support and principally between the rails 10 at a position above the pit 12, the support constituting largely the valve 19 though also including plate 32 and possibly a part of the road bed or ground, also including some cross ties which support the rails 10. The conveyor 14 will be in the position illustrated in Fig. 1 of the drawings as is the truck 17 which of course will initially be normally empty.

As the coal is discharged from the car 11 by which it flows under the influence of gravity, the rate of feed of the coal to the conveyor 14 is controlled by the valve 19, including particularly the adjustable horizontal slide plate 24 by which the feed rate to the conveyor 14 will be adjusted so as to do no harm to the tall flights thereof which

are employed because of the necessary elevation of the coal for discharging into the truck 17.

There will be a minimum loss of spillage over the guide plates 16 because of their close association with the side walls 13 of the pit 12. After the truck 17 is loaded the feed to the conveyor 14 may be shut off by closing the valve 19, and this may be done even though the plates 21, 22 and 24 are substantially covered with coal by virtue of the remotely operable hand wheel 31.

There is another important feature of the slide valve 19. It is to be noted that this slide valve in effect forms a part of the road bed. The railroad companies are very careful in granting permits to place pits under their rails because of the danger to persons that may be walking along the road bed, it being a notorious fact that small boys like to walk along railway road beds and an open pit is always a hazard for them as well as others who do likewise. The valve 19 is a very important safety factor because when there is no car 11 above the pit, the plate 24 is adjusted to its completely closed position and this makes it impossible for anyone walking along the road bed to fall into the pit 12. For this reason the valve 19 is useful not only when a coal car 11 is to be emptied but is useful when there is no coal car 11 on the tracks 10 above the pit 12.

Obviously those skilled in the art may make various changes in the details and arrangement of parts without departing from the spirit and scope of the invention as defined by the claim hereto appended, and I therefore wish not to be restricted to the precise construction herein disclosed.

Having thus described and shown an embodiment of my invention, what I desire to secure by Letters Patent of the United States is:

Apparatus of the class described comprising car rails, a pit below said rails, means for supporting material discharged from a car between said rails, including a control valve adapted to control the discharge of material from said supporting means to said pit comprising a stationary plate extending between said rails and a movable plate also extending between said rails which when moved to valve opening position forms a substantially continuous opening from one rail to the other.

FRANK DE YOUNG.
